UNITED STATES PATENT OFFICE.

ALFRED C. EINSTEIN, OF ST. LOUIS, MISSOURI.

DESIGN FOR A REFLECTOR.

44,092.

Specification for Design.

Patented May 27, 1913.

Application filed February 10, 1913. Serial No. 747,567. Term of patent 14 years.

To all whom it may concern:

Be it known that I, ALFRED C. EINSTEIN, a citizen of the United States, residing at St. Louis, Missouri, have invented a certain new, original, and ornamental Design for a Reflector, of which the following is a specification, reference being had to the accompanying drawing, forming part thereof.

Figure 1 is a side elevational view of my

new design; Fig. 2 is a bottom plan view thereof.

I claim:

The ornamental design for a reflector, as shown.

ALFRED C. EINSTEIN.
